United States Patent Office

Des. 186,348
Patented Oct. 13, 1959

186,348

ASH TRAY

Eric Olsen, Dundee, Ill., assignor to Frank J. Curran Co.,
Downers Grove, Ill., a corporation of Illinois

Application May 14, 1959, Serial No. 55,903

Term of patent 14 years

(Cl. D85—2)

Fig. 1 is a top perspective view of an ash tray, showing my new design;

Fig. 2 is a side view thereof taken along the lines 2--2 of Fig. 1; and

Fig. 3 is a bottom perspective view thereof.

I claim:
The ornamental design for an ash tray, substantially as shown.
